RAZOR AND MAGAZINE COMBINATION

Joseph Muros, Newtonville, Mass., assignor to
Gillette Safety Razor Company, Boston, Mass.,
a corporation of Massachusetts

Application December 11, 1947, Serial No. 790,995

7 Claims. (Cl. 30—40)

1 This invention comprises a novel safety razor and blade magazine combination and includes within its scope a novel process of transferring longitudinally slotted blades from a magazine-enclosed stack to a safety razor having blade-locating projections.

It is extremely desirable to transfer fresh sharp razor blades from the package or magazine in which they have been packed by the manufacturer and distributed to the customer without impairing the keenness of the shaving edge of the blades by contact with a wrapper or other object. The shaving edge of a safety razor which has been brought to a high degree of keenness by the manufacturer is very fragile and its shaving qualities are seriously impaired by the slightest contact. It is difficult for the user to unwrap a blade of this kind without drawing its edge across the paper of the wrapper or envelope or contacting it with some part of the razor in presenting the blade thereto.

The object of the present invention is to insure the transfer of one blade at a time, as required by the user, from a magazine in which the blades have been packed and are safely maintained, and direct it to the blade seat of the safety razor without the necessity and without liability of accidental contact of the shaving edge or edges of the blade. My invention is herein illustrated in connection with a safety razor of the type disclosed in my U. S. Letters Patent No. 2,009,272, dated July 23, 1935, and a blade magazine of the type disclosed in co-pending application Serial No. 37,723 filed July 8, 1948, which application is a continuation of Serial No. 758,025 filed June 30, 1947 and now abandoned, although the invention is not limited to safety razors and magazines of this or any other specific type but is of general application. In the illustrated form, however, the safety razor is provided with a blade-locating bar shaped to receive the slot of a longitudinally slotted razor blade and this bar for the purposes of the present invention is provided with a hook portion. The magazine employed in association therewith contains a stack of unwrapped blades which are arranged to be partially ejected, one by one, by traction of the user's thumb upon the flat surface of the uppermost blade in the stack. In one aspect, the process of my invention is characterized by the steps of partially ejecting a blade from the magazine by surface engagement until one end of its slot is exposed, then engaging the hook of the locating bar in the exposed end of the blade slot and finally drawing the blade from

the magazine by a separating movement of the magazine and razor and allowing the blade to settle itself upon the blade seat of the razor, being correctly positioned by the blade-locating bar. It will be observed that in carrying out this process the only contact with the blade is that required for the partial ejection thereof and that this is effected by contact only with the flat face of the blade while its shaving edges are safely concealed and protected. Complete removal of the blade from the magazine is effected by engagement of a razor part with an internal edge of the blade, and here again in this stage of the transferring process there is no danger of contact with the shaving edge of the blade and no reason for such contact. On the contrary, the entire transferring process is carried out by engaging the surface and internal edges of the blade in areas or at locations remote from its cutting edges. Preferably and as herein shown, the safety razor may be equipped with a hook-shaped element designed for convenient and secure engagement with the partially ejected blade, and the magazine may be provided with guiding means which insure or assist in locating the magazine in the safety razor in the most advantageous relation for effecting the transfer of a blade from one to the other.

These and other features of the invention will be best understood and appreciated from the following description of a preferred manner of carrying out the process of the present invention as illustrated in the accompanying drawings; in which—

35 Fig. 1 is a view in perspective showing a magazine and safety razor assembly with a blade partially ejected from the magazine and engaged by the razor;

40 Fig. 2 is a corresponding view showing the magazine separated from the razor, and the blade deposited upon the blade seat of the razor; and

45 Fig. 3 is a fragmentary view in perspective of one end of the magazine.

The safety razor herein shown is in its general construction similar to that of U. S. Letters Patent No. 2,009,272 above identified, to which reference may be had for further details of its construction. It comprises a handle 10 carrying a substantially flat guard member which provides the blade seat 11 of the safety razor. Rising through a slot in the blade seat is the elongated blade-locating bar 12, this being carried by a longitudinally movable spindle 13 having a tapering upper end shown in Fig. 2. The bar 12 is

provided at each end with an overhanging shoulder 24 giving it a hooked formation. Preferably and as herein shown the hooked formation is effected by an indentation in the end wall of the bar 12, the upper edge or wall of the indentation being comparatively short and extending inwardly, and the lower edge or wall comparatively long and gradually inclined outwardly, thus providing a guide edge or surface for directing the blade downwardly into position on the blade support or seat. The cap of the razor comprises sections 14 and 15 pivotally mounted on a spider 23 which is carried by and moved by means of the spindle 13. In Figs. 1 and 2, the cap sections 14 and 15 are shown in their open position and it will be understood that after a blade has been positioned upon the blade seat the cap sections are closed and the blade transversely flexed and held in shaving position.

The blade magazine 16 is rectangular in outline and provided with a thumb opening 17 in its upper wall and a blade-exit opening 18 in each of its end walls. As supplied to the user, it contains a stack of ten or twenty thin, flexible double-edged blades 21 having an elongated median slot 22 and unsharpened end portions of reduced width as compared to the body of the blade. These blades are maintained in staggered relation within the magazine and may be ejected, one by one, through the blade exit slot 18 by traction exerted on the upper surface of the uppermost blade in the stack by the finger or thumb of the user. The blade stack is maintained in the magazine with the shaving edges of the blade carefully spaced from the walls of the magazine by an upstanding rim 25 of substantially the same narrow width as the blade-locating, and in its ejecting movement each blade is safely guided by engagement of its slot with the rib 25 and also by a centrally disposed rib 19 projecting downwardly from the upper wall of the magazine. The outer end of this rib is shown in Fig. 3. The rib 19 at the exit slot, the rib 25 within the magazine, and the blade-locating bar 12 of the razor are all of substantially the same width, that is to say, they are designed to receive with slight clearance the median slot 22 of the blades being handled.

The magazine is provided with external guiding means herein shown as a groove 20, shaped to receive the upper edge of the blade-locating bar 12 and to center the magazine thereon. It will be apparent that any cooperating guiding elements provided respectively in the safety razor and the magazine would be satisfactory for effecting this purpose.

In carrying out the process of transferring a blade from the magazine to the razor, the user first partially ejects the uppermost blade from those contained in the magazine by surface engagement exerted through the opening 17 as suggested in Fig. 1. In this movement, the blade is guided by the internal rib 25 of the magazine and the guide rib 19 at the exit slot. The magazine is then presented to the open razor and registered in the proper transverse position by engaging the groove 20 of the magazine with the top edge of the bar 12, at the same time hooking the end of the bar through the slot of the blade, all as suggested in Fig. 1. In these preliminary steps, the engagement of the groove 20 with the bar 12 aligns the blade-locating guiding ribs 25 and 19 of the magazine with the blade-locating bar 20 of the razor. The user now draws the magazine and razor apart, moving them from the position shown in Fig. 1 to some such position as that shown in Fig. 2. In this separating movement

the blade is fully withdrawn from the magazine and as soon as it is freed therefrom it passes freely over the bar 12 and settles itself in position upon the blade seat 11, where it may be immediately clamped and retained in shaving position.

It will be observed in carrying out the process above outlined, the user engages only the flat surface of the blade in the magazine and it is impossible for him to contact the sharp edges of the blade. Similarly, when the ejecting force is transferred to the razor the engagement of the blade is through the medium of an internal edge provided by the blade slot 22 in a location remote from the cutting edges of the blade. The result is that the blade is controlled positively throughout its ejecting movement so that its shaving edges are carefully prevented from accidental contact and that it is delivered in final shaving position in intact condition.

Having thus disclosed my invention and described in detail the preferred manner of carrying out my novel process, I claim as new and desire to secure by Letters Patent:

1. For use in transferring a longitudinally-slotted double-edge blade into its proper position in the opened head of a unitary razor having an elongated blade-locating bar receivable in the slot of said blade and wherein the bar has a notch therein on at least one end thereof, a generally rectangular container adapted to receive therein the said blade and having an end exit opening, means permitting said blade to be partially ejected through said exit opening, an end portion of said container having a guide-groove on its underside arranged to receive the ride along the ridge of said blade-locating bar while the container is disposed at an angle to said blade-locating bar.

2. In a safety razor for use with an insertable centrally slotted blade, a support for the blade, a positioning bar associated with said support and adaptable to engage the slot of the blade, at least one end of the positioning bar being formed with a notch for engagement with a terminus of the slot during insertion of the blade into the razor, said notch comprising an indentation the upper wall of which is comparatively short and extends inward and the lower wall is comparatively long and gradually inclined outward to provide a guide for the blade toward the support surrounding said bar, and means for thereafter positioning said blade on said support.

3. In a safety razor for use with an insertable centrally slotted blade, a support for the blade, a positioning bar associated with said support and adapted to be positioned between the end walls of the blade slot when the blade is in position for use, said bar having on at least one of its ends means for facilitating rapid and accurate insertion of a blade onto said support from a blade magazine, said means comprising a notch arranged with its deepest portion adjacent the top of said bar and an inclined guide wall leading outwardly from such deepest portion of the notch toward the bottom of said bar, whereby an end wall of the slot of a blade partially projected from the magazine is engaged by said notch to hold the blade until it is completely released from the magazine, the released blade then falling by gravity into position on said support under guidance of said inclined wall, and means for thereafter clamping said positioned blade onto said support.

4. A safety razor for use with an insertable centrally slotted blade including a support for

the blade, and a positioning bar associated with said support and adaptable to engage the slot of the blade, at least one end of the positioning bar being formed with a notch for engagement with a terminus of the slot during insertion of the blade into the razor, said notch comprising an indentation the upper wall of which is comparatively short and extends inward and the lower wall is comparatively long and gradually inclined outwardly to provide a guide for the blade toward the support surrounding said bar, a magazine having a blade-locating rib of substantially the same width as said razor bar, a blade exit slot at one end and a finger opening in its top wall, and a stack of unwrapped blades in the magazine having central slots receiving the blade-locating rib of the magazine and each being movable by surface engagement for partial ejection through the exit slot and being thereupon exposed for engagement by the bar of the razor as aforesaid, whereby the blades may be individually transferred from the magazine onto the support in the razor.

5. A safety razor for use with an insertable centrally slotted blade including a support for the blade, and a positioning bar associated with said support and adaptable to engage the slot of the blade, at least one end of the positioning bar being formed with a notch for engagement with a terminus of the slot during insertion of the blade into the razor, said notch comprising an indentation the upper wall of which is comparatively short and extends inward and the lower wall is comparatively long and gradually inclined outwardly to provide a guide for the blade toward the support surrounding said bar, and a magazine containing such slotted blades and having an exit slot at one end and a groove in its bottom shaped to engage the bar of the razor for maintaining alignment of the razor and magazine during blade transfer.

6. A safety razor for use with an insertable centrally slotted blade including a support for the blade, and a positioning bar associated with said support and engageable with the slot of the blade, at least one end of the positioning bar having a notch arranged with its deepest portion adjacent the top of said bar for engagement with a terminus of the slot during insertion of the blade into the razor, and a blade magazine adapted to contain a stack of such slotted bare blades and operable in conjunction with said razor to transfer the contained blades singly from the magazine onto the support in the razor, said magazine including a casing having an end blade-exit opening, a blade-locating rib inside said casing shaped to fit in the longitudinal slots of said blades and guide them during at least part of their discharge movement, the casing including a

thumb-receiving opening overlying the blade stack location and extending in the direction of the blade-exit opening and being of sufficient length in said direction to permit the uppermost contained blade to be slid forwardly directly by the user's thumb, in a single stroke, by an amount sufficient to shift the leading terminus of the blade slot outwardly of said casing and expose it for direct engagement with the notch in the positioning bar of the razor, whereby the thus partially-advanced engaged blade may thereafter be pulled completely out of the magazine casing by separational movement of the magazine with respect to the razor, causing the extracted blade to settle down over the positioning bar and onto the support in the razor without further manipulation of the blade.

7. A safety razor for use with an insertable centrally slotted blade including a support for the blade, and a positioning bar associated with said support and engageable with the slot of the blade, at least one end of the positioning bar having a notch arranged with its deepest portion adjacent the top of said bar for engagement with a terminus of the slot during insertion of the blade into the razor, and a blade magazine adapted to contain a stack of such slotted bare blades and operable in conjunction with said razor to transfer the contained blades singly thereinto, said magazine including means permitting the partial ejection of one of said blades sufficiently to expose the terminus of the blade slot beyond the magazine end for coupling with the notch in the positioning bar of the razor, said magazine being so constructed and arranged as to permit the presentation of the partially ejected blade at an acute angle with respect to said positioning bar during the coupling of the two, whereby subsequent separational movement of the magazine with respect to the razor extracts the angularly related blade completely from the magazine and frees it to settle itself down over the positioning bar and onto the support in the razor.
